UNITED STATES PATENT OFFICE.

WILLIAM J. KAPPEL, OF MILWAUKEE, WISCONSIN, ASSIGNOR TO MARCUS SAX AND ISADORE SAX, COPARTNERS DOING BUSINESS AS SAX BROS., OF MILWAUKEE, WISCONSIN.

COMBINATION SHOE FLEXOR AND STRETCHER.

Application filed September 16, 1927. Serial No. 219,931.

This invention relates to a combination shoe flexor and stretcher.

Objects of this invention are to provide a novel form of shoe stretcher and flexor which is so constructed that it may be employed to stretch a shoe, flex the counter or flex or stretch any desired portion, and which is so made that it may be locked in position with the shoe left thereon so that the shoe may be held in a stretched condition for any desired length of time.

Further objects are to provide an adjustable member adapted to be inserted within the toe of the shoe and to receive either a small or large toe, such member being readily detachable from the main portion of the apparatus without requiring auxiliary tools or other means.

A further object is to provide a second adjustable member which may be moved inwardly or outwardly to accommodate shoes of different lengths.

In general, this invention is an improvement over that disclosed in my prior Patent No. 1,424,166, of August 1, 1922, for shoe counter flexor.

An embodiment of the invention is shown in the accompanying drawings in which:

Figure 1 is a side elevation partly in section of the device;

Figure 2 is a plan view of the toe receiving portion detached from the remainder of the machine;

Figure 3 is a sectional view on the line 3—3 of Figure 1;

Figure 4 is a sectional view on the line 4—4 of Figure 1;

Figure 5 is a plan view of the structure shown in Figure 4;

Figure 6 is a section through the main pivot pin and adjacent portions of the machine;

Figure 7 is a sectional view on the line 7—7 of Figure 1.

Referring to the drawings, it will be seen that the machine is provided with a standard 1 equipped with a flange 2 adapted for attachment to any suitable support, such as a table top 3. The standard 1 continues upwardly and thereafter bends forwardly to provide a projecting arm 4. It is also provided with an upper arm or lip 5 which receives the toe engaging member 6. The arm 5, it is to be noted, is provided with a headed and shouldered screw 7, as indi-

cated in Figure 1. The toe receiving portion 6 is shown most clearly in Figure 2, from which it will be seen that it is provided with a slot 8 adapted to interlock with the screw 7 and the slot is provided with an enlarged opening 9 adapted to receive the head of the screw. This toe receiving portion is provided with rounded ends, the end 10 being relatively small and adapted for engagement with the small sized shoe, and the end 11 being relatively large for a medium or large sized shoe.

A hand lever 12 is pivoted by means of the pivot pin or bolt 13 to the standard and it is preferable to form the hand lever 12 with an opening 14 through which the standard 1 passes, as shown in Figure 6. This gives a very secure pivotal support and permits the device to be freely used with any desired degree of pressure without any danger of breaking at the pivot point. The hand lever 12 is provided at one end with a handle and is also provided with a serrated or notched lower edge 15 (see Figure 1). This notched edge cooperates with a pin 16 carried by a sliding member 17 which straddles the hand lever, as shown in Figures 1 and 4. The member 17 is provided with an upwardly and rearwardly projecting bulged or rounded heel engaging member 18. This member may be made convex on its rear side and concave on its front side, as indicated in Figure 5. It is apparent that the member 17 may be slipped forwardly or rearwardly upon the hand lever and when in engagement with the shoe will rock, as shown in Figure 1, causing the pin 16 to lock with reference to the notched edge 15 of the hand lever. It is apparent that the member 17 may be quickly adjusted along the hand lever when the pressure is released in order to accommodate any sized shoe.

It is to be noted also that the hand lever is provided with a serrated or notched lower edge 19 on its under side in front of the pivotal bolt or pin 13. This notched edge is adapted to cooperate with a swinging latch 20 or prop so that the hand lever may be locked in adjusted position, as shown in Figure 1, to retain the shoe under tension for any desired length of time. It is to be noted also from reference to Figures 1 and 7, that the forward ends of the hand lever and of the arm 4 of the standard may be

used for stretching any portion of the shoe by suitably forcing the hand lever in a counter clock-wise direction. Under these conditions, a second flap or prop 21 may cooperate with the notched edge 15 to lock the hand lever in position.

Further, it is to be noted from Figures 1 and 7, that the device may be used for flexing the counter or any other portion of the shoe desired, as in my above noted patent. The forward end of the hand lever 12 is provided with a pair of arms 12' (see Figure 7) which cooperate with the centrally positioned arm 4 of the standard. The counter may be inserted between these arms and the hand lever pressed downwardly in a clock-wise direction to flex the counter, as in my above noted patent.

It will be seen that a very simple and highly effective type of shoe stretching and flexing machine has been provided which may be readily adjusted to accommodate any type of shoe, and which is easy to operate.

Although the invention has been described

in considerable detail, such description is intended as illustrative rather than limiting as the invention may be variously embodied and as the scope of such invention is to be determined as claimed.

I claim:

A combined shoe flexing and stretching device comprising a standard having a forwardly projecting arm and having an upper spaced arm, a toe engaging portion carried by said upper arm, a hand-lever pivoted to the standard, an adjustably mounted heel engaging portion carried by said hand-lever, said hand-lever having a handle at one end and having a pair of spaced arms adjacent its other end positioned in proximity to the first mentioned arm of said standard, and means for locking said hand-lever in any desired position.

In testimony that I claim the foregoing I have hereunto set my hand at Milwaukee, in the county of Milwaukee and State of Wisconsin.

WILLIAM J. KAPPEL.
